UNITED STATES PATENT OFFICE.

JAMES M. TEAHEN, OF DETROIT, MICHIGAN.

FLUSHING-TANK.

1,241,470.

Specification of Letters Patent. Patented Sept. 25, 1917.

Application filed November 6, 1916. Serial No. 129,841.

To all whom it may concern:

Be it known that I, JAMES M. TEAHEN, a citizen of the United States of America, residing at Detroit, in the county of Wayne 5 and State of Michigan, have invented certain new and useful Improvements in Flushing-Tanks, of which the following is a specification, reference being had therein to the accompanying drawings.

10 The invention relates to tanks formed of plastic compositions, and more particularly to that class in which the material used is a calcium resinate. The invention comprises various features of construction as 15 hereinafter set forth.

In the drawings:

Figure 1 is a perspective view of the tank and cover;

Fig. 2 is a cross-section through the rear 20 wall of the tank showing the manner of securing the metallic hanger thereto;

Fig. 3 is a longitudinal section on line 25 x—x Fig. 2; and

Fig. 4 is a cross section through the lug. 25 Heretofore composition tanks have been formed by the molding of the plastic material, but difficulty has been experienced in the mounting of said tanks in position for use; thus, as the material is somewhat lack-

30 ing in tensile strength there is danger of breaking at the point of support. It is also difficult to secure to the tank any kind of hanger, anchored within the plastic body, as the latter is molded under hydraulic pres-

35 sure. With my improved construction I have provided the tank with a hanger which is securely anchored thereto without interfering with the process of construction, said hanger being also adapted for easy securing 40 to the wall or other point of support, and not in any way interfering with the finish of the structure.

In detail, A is the tank, which may be of any suitable design, and B is the cover therefor. C is a hanger, preferably in the form 45 of a metallic angle bar having a horizontal flange D of substantially the same width as the thickness of the wall of the tank, and provided with downwardly struck out 50 prongs E for anchoring in the plastic body. The hanger C is also provided with a vertical flange F substantially flush with the rear face of the wall of the tank and having

slots G with which the securing screws may be engaged and adjusted to register with the 60 studding or other support. The rear wall H of the tank is recessed for the reception of the hanger C, so that the upper edge of the flange F is substantially flush with the upper edge of the tank. This permits of 65 engaging the cover without interference with the hanger. In use, when the hanger is secured to the support the tank will be held in position and the weight is so distributed through the various anchoring 70 prongs E as to avoid danger of the tank breaking loose from the hanger.

In the shipment of the tank and its cover it is desirable to secure the same so as not to mar the finished exterior. The tank 70 can be easily clamped within a container by bearings upon the bottom and upper edge thereof, but the cover being finished on both the top and sides is more difficult to secure. I therefore preferably form the cover with 75 lugs I projecting from the underside of the top, said lugs providing a sufficient mass of material for the embedding 80 of a nut or other securing means J. Thus screws or other securing means may be engaged 85 with the nuts J to clamp the cover in position within the container, while the lugs I are so positioned as to avoid interference with any of the mechanism placed within the tank.

What I claim as my invention is:

1. The combination with a composite tank, of an anchoring device therefor, comprising a metallic angle strip extending longitudinally of the wall of the tank and in a recess therein, with its upper edge substantially flush with the upper edge of the wall, said strip having anchoring prongs embedded in the wall and a slotted flange for engagement with the securing devices, and a cover seated 95 upon the upper edge of said tank.

2. The combination with a composite tank, of an anchoring device therefor, comprising a metallic angle strip having a vertical flange arranged substantially flush with the 100 rear face of the tank wall and a horizontal flange extending along the face of a recess in said wall, said horizontal flange being provided with struck-out prongs embedded in the composite body and the vertical 105 flange being provided with a series of slots

for the adjustable engagement of securing devices, and a cover seated upon the upper edge of said tank.

3. The combination with a composite open-topped tank having a recess at the top of one of its walls, of an anchoring device for said tank within said recess, said device comprising a metallic angle strip having

a horizontal flange rigidly engaged with the recessed wall, and having a vertical flange, 10 the upper edge of which is substantially flush with the upper edge of said wall, and a cover seated upon the upper edge of said tank.

In testimony whereof I affix my signature. 15

JAMES M. TEAHEN.
